UNITED STATES PATENT OFFICE.

EDWARD F. WALSH, OF GRACEMONT, OKLAHOMA TERRITORY.

METALLIC RAILROAD-TIE.

SPECIFICATION forming part of Letters Patent No. 793,407, dated June 27, 1905.

Application filed April 3, 1905. Serial No. 253,491.

To all whom it may concern:

Be it known that I, EDWARD F. WALSH, a citizen of the United States, residing at Gracemont, in the county of Caddo, Territory of Oklahoma, have invented certain new and useful Improvements in Metallic Railroad-Ties, of which the following is a specification.

This invention relates to metallic railroad-tie construction, and comprises a novel form 10 of tie in connection with special rail clamping or holding means combined with the tie structure in such a manner as to promote the rigidity of the rails and firmly brace the latter when in position upon the tie.

15 The invention aims to secure a metallic tie which will obviate the necessity of use of the present wooden ties and which because of the provision of the rail-clamping means will effect a great saving of material, such as track-spikes, joint-bars, bolts, and like parts. The 20 disadvantages of the wooden-tie structure are obvious, and the metallic tie embodying this invention is designed to prevent kinking or buckling of the rails, to facilitate removal and 25 replacement thereof, the metallic tie of course having longer life and greater wearing qualities.

For a full description of the invention and the merits thereof and also to acquire a knowledge 30 of the details of construction of the means for effecting the result reference is to be had to the following description and accompanying drawings, in which—

Figure 1 is a top plan view showing the invention as when applied. Fig. 2 is a vertical longitudinal sectional view through a tie embodying a construction according to the invention. Fig. 3 is a detail perspective view of the tie, chair members, and rails removed. 35 Fig. 4 is a detail perspective view of one of the chair members. Fig. 5 is a view in elevation of the tie, rails in position, and shown in section. Fig. 6 is a transverse sectional view on the line X-X of Fig. 5. Fig. 7 is a 40 detail perspective view of the wedge member. Fig. 8 is a detail perspective view of the wedge member.

Corresponding and like parts are referred to in the following description and indicated in all the views of the drawings by the same reference characters.

45 In the practical embodiment of the invention

the body of the tie is of hollow form and when viewed in cross-section is of approximately oblong structure, comprising the base 1, the sides 2, and the top or uppermost portion 3. The top 3 of the tie is cut away at its 55 ends, as shown at 4, to receive chair members 5, which are designed to positively engage sides of the rails in order to support the latter rigidly upon the tie. It is preferred to use three of the chair members 3 for each tie, 60 and said chair members are transversely displaceable from the tie. Two of the chair members 5 at one end of the tie coöperate with each other to embrace the rail 6 upon opposite sides, the third chair member 5, however, coöperating with a rigid chair member 7 at one end of the tie. The rigid chair member 7 is of somewhat the same formation as the body of the other chair members 5; but the member 7 is formed integrally with the tie 70 and is of course fixed in its position. The outer edge portions of the chair members 5 are beveled, as shown at 8, so as to fit beneath undercut portions 9 in the top 3 of the tie, said undercut portions 9 being located at the sides 75 of the cut-away portions 4, which receive the chair members. Horizontal webs 10 connect the sides 2 of the tie and extend across the cut-away portions 4, said webs forming base portions upon which the bases of the rails 6 80 directly rest. The webs 10 are of course integrally formed with the tie and are in a plane lower than the top 3 thereof. Integrally formed with the chair members 5 and extending downwardly from the under sides 85 thereof are depending webs 11, provided at the lower edge portions with longitudinal lateral flanges 12. The sides 3 of the tie are provided with L-shaped slots 13 to admit of engagement of the lower portions of the flanged 90 webs 11 beneath the webs 10 of the tie to prevent upward displacement of said chair members when the latter are in position embracing the rails. The chair members 5 and 7 have the under sides thereof curved near the 95 adjacent portions, so as to snugly fit against the base of the rails with which they engage, and the uppermost portions of the chair members are provided with horizontal openings 14, through which bolts or like fastening may 100

be passed, said bolts passing through the webs of the rails also, securing the latter positively to the chair members. To prevent the chair members 5 from being laterally displaced 5 from the tie, wedge members 15 are utilized, and said members are adapted to engage notched portions 16 and 17 in the tie and in the chair members 5, respectively, thereby interlocking therewith. The notched portions 10 16 are located between the sides of the tie and in the top 3 at sides of the cut-away portions 4. When the wedge members 15 are driven downwardly into the space formed by the notches 16 and 17, which notches are 15 adapted to register when the chair members 5 are disposed upon the tie, said wedge members tend to force the chair members 5 hard against the sides of the rail to brace the latter firmly in a manner which will be readily 20 apparent.

It will be noted that the construction of the tie and the rail-engaging means carried thereby is comparatively simple and enables the rails to be placed in position very quickly 25 without the use of a great many parts which are ordinarily employed in wooden-tie road structure. Further, if it is desired to remove one of the ties from the track for purposes of repair or the like it will be seen that it is 30 only necessary to remove the members 15, and the members 5 may be laterally displaced and permit of lowering of the tie from the rails and removal thereof.

The various advantages of the tie structure 35 will be apparent to those versed in this art.

Having thus described the invention, what is claimed as new is—

1. In a metallic railroad-tie, the combination of a tie comprising a body, transversely-40 displaceable chair members mounted upon said body and having interlocking connection therewith, and wedge members carried by the body of the tie for forcing the chair members against the rails, said wedge members interlocking with the chair members to prevent 45 transverse displacement thereof.

2. In a metallic railroad-tie, the combination of a tie comprising a hollow body having the top portion thereof cut away near the ends, 50 horizontal webs connecting the sides of the tie at the cut-away portions and in a plane lower than the top of the tie, said horizontal webs forming base portions upon which the rails are adapted to rest, chair members in the cut-away portions in the top of the tie, and wedge members coöperating with said chair members 55 to position the same.

3. In a metallic railroad-tie, the combination of a tie comprising a hollow body having

the top portion thereof cut away near the ends, 60 horizontal webs connecting the sides of the tie at the cut-away portions and in a plane lower than the top of the tie, said horizontal webs forming base portions upon which the rails are adapted to rest, chair members in the cut-away portions in the top of the tie, webs depending from the under sides of the chair members, and flanges projecting from said webs for interlocking connection with the tie. 65

4. In a metallic railroad-tie, the combination of a tie comprising a hollow body having the top portion thereof cut away near the ends, 70 horizontal webs connecting the sides of the tie at the cut-away portions and in a plane lower than the top of the tie, said horizontal webs 75 forming base portions upon which the rails are adapted to rest, chair members in the cut-away portions in the top of the tie, webs depending from the under sides of the chair members, flanges projecting from said webs 80 for interlocking connection with the tie, and wedge members arranged between the outer edge portions of the chair members and the adjacent portions of the top of the tie to prevent lateral displacement of the chair members 85 from the tie.

5. In a metallic railroad-tie, the combination of a tie comprising a hollow body having the top portion thereof cut away at the ends, 90 the top portion of the tie at the sides of the cut-away portions being undercut, horizontal webs connecting sides of the tie at the cut-away portions of the top, said webs being arranged in a plane lower than the top of the tie, the sides of the tie at the cut-away portions being provided 95 with L-shaped slots, detachable chair members mounted in the cut-away portions of the top of the tie, webs depending from the under sides of said detachable chair members, flanges projecting laterally from said depending webs, the depending webs and flanges being received in the L-shaped slots in the sides of the tie and interlocking with said tie, rails upon the horizontal webs of the tie, a rigid chair member at one end of the tie coöperating with an 100 adjacent detachable chair member, fastenings passing through the upper portions of the chair members and the rails aforesaid, and wedges between the outer edge portions of the detachable chair members and the adjacent 105 portions of the top of the tie.

In testimony whereof I affix my signature in presence of two witnesses.

EDWARD F. WALSH. [L. S.]
